[57] CLAIM

The ornamental design for a three dimensional game, as shown and described.

DESCRIPTION

FIG. 1 is a front, top and side perspective view of the three dimensional game embodying the design of the present invention;

FIG. 2 is a front elevational view thereof, the rear being a mirror image of the front shown in FIG. 2;

FIG. 3 is a side elevational view thereof, the side opposite being a mirror image of the side shown in FIG. 3;

FIG. 4 is a top plan view thereof; and,

FIG. 5 is a bottom plan view thereof.
